(57) **CLAIM**

I claim a collapsible box, as shown and described.

DESCRIPTION

FIG. 1 is a front view of the collapsible box showing my new design;

FIG. 2 is a top view thereof;

FIG. 3 is a rear view thereof;

FIG. 4 is a bottom view thereof;

FIG. 5 is a left side view thereof;

FIG. 6 is a right side view thereof;

FIG. 7 is a perspective view thereof;

FIG. 8 is an additional perspective view thereof showing the collapsible box in an open position; and,

FIG. 9 is an additional perspective view thereof showing the collapsible box in a flattened position.
